UNITED STATES PATENT OFFICE.

GEORGE G. FLOYD, OF RIVERSIDE, ILLINOIS.

DESIGN FOR A CASING FOR RAZOR-BLADE SHARPENERS.

51,550.

Specification for Design.

Patented Dec. 11, 1917.

Application filed June 9, 1917. Serial No. 173,891. Term of patent 14 years.

To all whom it may concern:

Be it known that I, GEORGE G. FLOYD, a citizen of the United States, residing at Riverside, in the county of Cook and State of Illinois, have invented a new, original, and ornamental Design for Casings for Razor-Blade Sharpeners, of which the following is a specification, reference being had to the accompanying drawing, forming a part thereof.

In the drawing;

Figure 1 is an end view of a casing for razor blade sharpeners illustrating my new design.

Fig. 2 is a plan view of the same, and
Fig. 3 is a view of the opposite end.

I claim:

The ornamental design for a casing for razor blade sharpeners, as shown.

GEORGE G. FLOYD.
